UNITED STATES PATENT OFFICE.

DANIEL C. RIPLEY, OF PITTSBURG, PENNSYLVANIA.

GLASS CASTER.

SPECIFICATION forming part of Letters Patent No. 289,027, dated November 27, 1883.

Application filed October 6, 1883. (No model.)

To all whom it may concern:

Be it known that I, DANIEL C. RIPLEY, of Pittsburgh, in the county of Allegheny and State of Pennsylvania, have invented a new 5 useful Improvement in Glass Casters; and I do hereby declare the following to be a full, clear, and exact description thereof, reference being had to the accompanying drawings, forming part of this specification, in which—
10 Figure 1 is a side elevation, partly in section, of my improved glass caster. Fig. 2 is a plan view of the same, partly in section on the line $x-x$ of Fig. 1. Fig. 3 is a cross-section on $y-y$, Fig. 2. Figs. 4 and 5 are plan 15 views of other forms of the caster.

Like letters of reference indicate like parts wherever they occur.

Heretofore glass casters have been made either with the bottle-receptacles projecting 20 independently of each other from a flat plate or disk which was mounted on a suitable stem or stand, or the stand itself was of dish shape, having its interior divided into bottle-receptacles by integral partitions extending across 25 the same. Both of these forms are open to objection. The first form requires an independent stand to support it, and the bottle-receptacles, as well as the disk or plate which supports them, are extremely liable to break, 30 being not only comparatively thin, but also totally unsupported and unprotected on the under side and outer edge. The second form, while having none of the objections urged to the first, is provided with partitions, which 35 must be made very thick and heavy, to prevent their being broken by hasty and careless replacing of the caster-bottles therein, to which they are exposed when in use. This increases the weight and cost extremely and detracts 40 from the beauty, and consequently salable qualities, of the article. It necessitates the use of a split plunger, which is more expensive and difficult to make and keep in repair than a plain one.

45 My invention is designed to obviate these various objections, and to give a simpler, cheaper, and generally better caster than the former ones mentioned.

Referring now to Figs. 1 and 2, the caster- 50 stand a , which is made by pressing by means

of a suitable mold and plunger, is in form like a shallow dish, the width of its interior cavity or receptacle, a' , and the shape of its sides a^2 being such as to receive and support a given number of bottles b . In the present instance 55 there are three bottles, which are normally adapted or shaped to fit into the receptacle or interior a' and against each other, and to be supported by the sides a^2 and by each other. The bottles b are interchangeable, and any one 60 may be put into the receptacle a' at either end or the middle, and when the other bottles are inserted will, in the absence of partitions, find its proper relative place. Thus the caster is fitted for easy and careless use, and not liable 65 to be damaged by the breaking of partitions. The sides and bottom are made of sufficient thickness to support and protect the bottles from being broken. The bottom of the stand constitutes the base of the article, unless it is 70 preferred to provide it with a foot; but I prefer it as shown, because there is then no danger of its being upset. Handle-flanges c are formed at the ends or sides.

In Fig. 4 I show a square caster for containing four bottles, and in Fig. 5 one shaped like a cross for containing five bottles, both having the characteristic features of my invention.

In addition to the advantages named, the 80 saving of the glass required to form the partitions enables me to reduce the cost of my improved caster, and thus bring it within the reach of persons of very limited means.

What I claim as my invention, and desire 85 to secure by Letters Patent, is—

The combination of a dish-shaped caster-stand, having a common receptacle for a given number of caster-bottles, with caster-bottles adapted to fit into said receptacle and against 90 each other, and to be supported by the sides of the stand and by each other, substantially as and for the purposes described.

In testimony whereof I have hereunto set my hand.

DANIEL C. RIPLEY.
